Specification of Letters Patent. Patented Nov. 13, 1917.

Application filed July 14, 1913. Serial No. 779,031.

To all whom it may concern:

Be it known that I, FRANCIS X. AUDET, a citizen of the United States, residing at New York, in the county of New York and State 5 of New York, have invented certain new and useful Improvements in Keyed Zithers; and I do hereby declare the following to be a full, clear, and exact description of the invention, such as will enable others skilled 10 in the art to which it appertains to make and use the same.

The present invention relates to keyed zithers, and its object is to provide playing devices whereby the playing of the instrument 15 is facilitated.

The playing devices include, in the present instance, spring hammers for striking the strings, each said hammer including a spring shank and a striker head carried 20 thereby. I have combined with such spring hammers playing keys and dampers or muting devices. I have arranged the playing keys according to the arrangement of the keys of a pianoforte, which are arranged 25 in two series, those for the flats or sharps being arranged in one series, and those for the naturals being arranged in another series. In order to compensate for the difference in arrangement between the two series of 30 keys I have arranged the spring hammers in two series and have made other compensatory provisions, to obtain uniformity of action and uniformity as to the volume and quality of the tones produced thereby.

35 The dampers or muting devices are carried by spring arms, which in turn are carried by the spring shanks of the playing hammers, the flexibility of said arms enabling the traverse of the muting devices 40 to be short in comparison to that of the hammers. The muting devices are arranged to engage the opposite side of the strings with reference to the striker heads. A combination including the arms that carry the 45 muting devices, and stops for arresting the striking movement of the hammer shanks enables the shanks to vibrate without being affected by the arresting of the muting devices in their retractive movement as the 50 hammers are moved toward the strings.

In the accompanying drawings which show a stringed musical instrument of the zither type embodying what is now considered the preferred form of the present invention, Figure 1 is a top plan view of the 55 instrument, and Fig. 2 is a transverse section on line X—X, Fig. 1, looking toward the right; Fig. 3 is an enlarged detail view of the hammers and actuating keys; Fig. 4 is a top plan view of the same; and Figs. 60 5 and 6 show one of the bridges in enlarged end and front views respectively.

The instrument shown in the drawings comprises the usual end frame pieces 1 and 2, upper sounding board 3, braces 4, lower 65 sounding board 5, and tuning pins 6. The strings are arranged in two portions or sections, one portion or section 7, hereinafter called the melody section, having its strings 8, 8 arranged in a single plane and tuned 70 for playing the air or melody, and the other section 9, called the accompaniment section, being provided with strings arranged in two intersecting planes (see Fig. 2) tuned in chord relation for playing the accompaniment. In the preferred construction as shown in the drawings, the strings in the melody section are tuned in the chromatic scale, a pair of strings tuned to each note 75 being provided to give the desired volume and quality of tone. In the accompaniment section the bass strings 10 are located in one of the intersecting planes, while the chord strings 11 are located in the other of the intersecting planes.

Formerly the melody was played by plucking or striking the appropriate strings in the melody section with a pick or other device held in the hand, and considerable skill was required of the performer to do this 80 with accuracy and celerity. Recently, in order to overcome this feature of disadvantage in the prior instruments, a series of hammers for striking the strings have been provided, arranged to be actuated directly 85 by the fingers of the performer or through the medium of keys. Such devices, however, have been of crude construction and unsatisfactory action, and have resulted in a limitation of the range or scope of the in- 90 95 100

strument, or a substantial increase in its size.

The present invention overcomes these objections by providing string-actuating devices for the instrument which are of simple and compact construction and of easy action whereby the range and scope of the instrument has been increased and the character and quality of the tone greatly improved. Preferably, resilient or spring hammers are employed whereby with one actuation a plurality of blows may be struck upon the strings, giving a tremolo effect. Actuating devices for the hammers are also used in the preferred construction, such devices comprising keys similar to the keys of the common pianoforte.

In the specific embodiment of the present invention shown in the drawings the hammers comprise resilient shanks 15 secured at one end to the fixed support 16 and carrying at their free end the striker head 17 of substantially greater width than the double string 8, 8, to insure contact with both strings when the shank of the hammer is depressed. To avoid increasing the size of the instrument or decreasing its range or capacity, and also for the purpose of employing actuating keys set in the ordinary pianoforte arrangement and obtaining substantially the same action for both rows of keys, these hammers are arranged in staggered relation in two series 18 and 19, the hammers of series 18 which strike the strings tuned to sharps and flats being located in vertical registration with the spaces between adjacent hammers in series 19 which strike the strings tuned to naturals.

40 In order to permit the hammer to vibrate when it is depressed and thus strike the string a plurality of blows, producing a tremolo effect, a stop 22 is provided on the support which carries the hammers, this stop in the preferred embodiment consisting of felt or similar yielding material. Preferably, a second stop 23 of similar material is provided which is located on the support intermediate the first stop and the point of attachment of the hammer. The purpose of this intermediate stop is to prevent objectionable vibration between stop 22 and the point of attachment of the hammer which might interfere with the proper action of the free end of the hammer. In playing the instrument, when both stops are provided, the spring shank 15 engages the stop 23 first, and then engages the stop 22. For the purpose of giving the hammers of both series the same effective vibration length, the line of the stops 22 for the hammers of series 18 is offset with relation to the line of the stops for the hammers of series 19 substantially the same distance

that the heads of hammers in series 18 are 65 offset from the heads of the hammers in series 19.

To permit the hammers of series 19 to be actuated without interference with the hammers of series 18, a clip or extension member 24 is attached to the shank of each of the hammers of series 19 at a point opposite the stop 22, the upper surface of said members 25 projecting above the shanks of the hammers of series 18 when the hammers of series 19 are depressed. A similar but shorter extension member 25 is secured to the shanks of the hammers in series 18.

75 While the above described construction may be used without playing keys, the performer in such case depressing the hammers by direct engagement of his fingers with the members 24 and 25 on the hammer shanks, I have shown playing keys pivoted at one end at 28 and 29 and engaging at 75 their free ends these members 24 and 25 secured to the shanks of the hammers. These keys are set in the common pianoforte arrangement, the keys 26 for actuating the hammers in series 19 which strike the strings 90 tuned to naturals being white and set in advance, or nearer to the performer than the keys 27, which are colored black and which actuate the keys tuned to sharps. To avoid excessive sliding action of the keys on the members 24 and 25, the pivots 28, 29 are arranged between the plane of the strings and the parallel plane to which the hammer heads are normally retracted. In the 95 illustrated embodiment of the invention these pivots 28 and 29 are as near as may be convenient to the points at which the shanks 100 are anchored to the support 16.

105 In the preferred embodiment of the present invention means are provided for muting the strings when it is desired that the tone or note shall cease, such means comprising muting devices arranged to be held out of contact with the string to permit the latter to sound, and to be held in contact with the string to stop the string from sounding. In the construction illustrated 110 in the drawing these devices comprise the spring arms 32 each secured at one end 33 to a hammer shank and extending beneath the hammer and between the pair of strings, and having its free end 34 substantially parallel with the strings, and carrying a head of felt, rubber tubing or other similar material 35 to contact with the strings and stop 115 their vibration. The muting device is so arranged that when the hammer is in its raised position the head 35 will be held in contact with the bottoms of both strings, the extent of upward movement of the hammers under the action of the resilient shanks 120 125 being limited thereby. When the hammer is depressed to sound a string the head

of the mute will be moved downwardly away from the strings and may, if desired, contact with the sounding board, remaining in this position as long as the hammer is 5 held depressed and it is desired the string shall sound.

The accompaniment to the melody is played upon the strings in the accompaniment section 9 either by striking the appropriate bass string in one of the intersecting planes and then the proper chord strings in the other plane, or striking both bass and chord strings at the line of intersection of the planes, the chord strings and appropriate basses being grouped together so that this may be done.

Heretofore strings have been arranged in intersecting planes by means of a pair of bridges of different heights at each end of the sounding board of the instrument. Such a construction, however, has been found objectionable for several reasons, among others that the difference in height between the two bridges at the same end of the instrument 25 was limited in practice owing to the excessive strain put upon the instrument by each slight increase in height of the bridge. As a result the planes of the strings were necessarily nearly coincident, that is, their angle 30 of intersection was small, and it was found necessary to strike the strings of each plane at so great a distance from the line of intersection that it required the movement of the hand from one side of said line to the other. Furthermore, the volume of tone emitted 35 from strings so arranged was limited and the quality of tone was inferior owing to the fact that the bridges for supporting these strings were at the extreme ends of the 40 sounding board and directly over the end frame pieces, the tension on the strings being so great that the use of a bridge resting upon the sounding board was absolutely prohibited.

In the specific embodiment of the present invention an intermediate bridge is employed having oppositely disposed string-engaging faces, the strings of one plane passing over the upper surface of the bridge 45 and tending to force the latter toward the sounding board, while the strings of the other plane pass beneath the lower surface of the bridge and tend to force the bridge away from the sounding board. By a proper arrangement of the strings upon the opposite sides of the bridge the downward pressure on the bridge may be counteracted to any desired extent, being exactly balanced, if desired, the bridge then being what may 50 be termed a floating bridge, without being in contact with the sounding board. In the preferred construction, however, there will be an excess of downward pressure sufficient to hold the bridge firmly against the sound-

ing board yet without danger of crushing the same. The vibrations of the strings are thus transmitted directly through the bridge to the sounding board, thereby greatly increasing the amplitude of vibration of the latter, with a corresponding increase in the 70 volume of tone, and with a superior quality of tone.

This improved form of bridge is shown in Figs. 5 and 6 and comprises a body portion 38 having a string-engaging upper surface 39 having a bridge wire 40 and provided at its lower surface with a slot 41 in the top of which is located the bridge wire 42, and also having the transverse string-receiving slots 43, the downwardly projecting portions 80 of the bridge between the longitudinal and transverse slots forming supporting feet to rest upon the sounding board of the instrument. The bass strings 10 are arranged to pass under the lower surface of the bridge, 85 while the chord strings 11 pass over the upper surface, and since there are twice as many chord strings as bass strings, although the basses are under heavier tension, the excess of downward pressure is sufficient to 90 hold the bridge with the desired firmness against the sounding board.

Since this intermediate or counterbalanced bridge may be made of much greater height than the prior form of bridges, the angle of 95 intersection of the planes of the accompaniment strings may be increased to such an extent that the performer may pluck or strike a bass string with his thumb and the chord strings with his finger without moving his hand, a feature of very decided importance, especially when the chord strings are tuned as above described to major and minor thirds alternately. If it is desired to still further increase the angle of intersection of the planes of strings or to avoid the use of an intermediate bridge of excessive height, two similar bridges may be employed, one near each end of the instrument. It will be noted that the height of the intermediate 100 bridge and its relation with respect to the bridge at the opposite end of the instrument determines the point of intersection of the planes of the accompaniment strings. By selection of proper heights for these bridges 105 this line of intersection may be placed at the most convenient point for the performer.

The manner of use and mode of operation of the instrument forming the subject of the present invention have already been sufficiently set forth in the foregoing description, and need not, therefore, be here repeated. It is to be understood that while the instrument shown in the drawings and described in the specification is the preferred 120 form of the present invention, the latter may be embodied in many different forms and arrangements, no particular form or arrange-

ment being essential except as set forth in the claims.

Having thus described the present invention, and the manner of its use, what I claim is:

- 5 1. A musical instrument, having, in combination, strings and means for supporting the same, spring hammers, and means for supporting the hammers in a plurality of overlapping series, substantially as described.
- 10 2. A musical instrument, having, in combination, strings and means for supporting the same, a plurality of series of spring hammers, and means for supporting the hammers with one series overlapping another series, and each hammer of one series located between hammers of another series, substantially as described.
- 15 3. A musical instrument, having, in combination, strings and means for supporting the same, a plurality of series of spring hammers of equal length, and means for supporting the hammers with one series overlapping another series, and each hammer of one series located between hammers of another series, substantially as described.
- 20 4. A musical instrument, having, in combination, strings and means for supporting the same, spring hammers and means for supporting the hammers in a plurality of superposed series, and means for actuating the hammers in any series without interfering with the hammers in another series, substantially as described.
- 25 5. A musical instrument, having, in combination, strings and means for supporting the same, spring hammers, means for supporting the same in a plurality of superposed series and means for actuating the hammers comprising members secured to the hammers in one series and projecting beyond the hammers in another series whereby the hammers of the first mentioned series may be actuated without actuating the hammers in the last mentioned series, substantially as described.
- 30 6. A musical instrument, having, in combination, strings and means for supporting the same in substantially the same plane, spring hammers, and means for supporting the hammers normally in inclined relation to the plane of the strings, said hammers being arranged in staggered relation in a plurality of series, substantially as described.
- 35 7. A musical instrument, having, in combination, strings and means for supporting the same in substantially the same plane, spring hammers, and means for supporting the hammers in a plurality of overlapping series in substantially parallel planes inclined to the plane of the strings, substantially as described.
- 40 8. A musical instrument, having, in combination, strings and means for supporting the same, spring hammers for striking the strings, a support to which one end of each hammer is attached, and a plurality of stops to be engaged by the spring hammer when the latter is depressed to strike the string, substantially as described. 65
- 45 9. A musical instrument, having, in combination, strings and means for supporting the same, spring hammers for striking the strings, a support to which one end of each hammer is attached, and a plurality of stops to be engaged progressively by each hammer from the support toward the free end of the hammer when the latter is depressed to strike the string, substantially as described. 70
- 50 10. A musical instrument, having, in combination, strings and means for supporting the same, a plurality of hammers each comprising a striker head and a spring shank, and a stop for each said shank, said hammers being arranged in staggered relation in a plurality of series, and said stops being arranged in staggered relation in a like number of series, to cause uniform action 75
- 55 11. A musical instrument, having, in combination, strings and means for supporting the same, a plurality of hammers each comprising a striker head and a spring shank, a stop for each said shank, and devices for actuating the spring hammers, each said device comprising an element arranged to contact with said stop when the hammer is in striking position, substantially as described. 80
- 60 12. A musical instrument, having, in combination, strings and means for supporting the same, spring hammers, a support to which the hammers are secured, and pivoted keys for actuating the hammers, the pivotal point of each key being between the plane of said strings and the parallel plane to which the head of the hammer is retractable, substantially as described. 85
- 65 13. A musical instrument, having, in combination, strings and means for supporting the same, spring hammers arranged in overlapping series, and keys pivoted at one end, the free ends of the keys actuating the hammers, and the keys set in chromatic piano-forte arrangement, substantially as described. 90
- 70 14. A musical instrument, having, in combination, strings, hammers for striking the latter, spring arms carried by said hammers, and muting devices carried by said spring arms, substantially as described. 95
- 75 15. A musical instrument, having, in combination, strings, hammers provided with resilient shanks, and muting devices com- 100
- 80 110
- 85 115
- 90 120
- 95 125

prising string-engaging members secured to the resilient shanks of the hammers, substantially as described.

16. A musical instrument, having, in combination, strings, spring shanks, striker heads carried by said spring shanks, and muting devices carried by said spring shanks, substantially as described.

17. A musical instrument, having, in combination, strings, hammers each comprising a spring shank and a striker head secured to

the latter, a stop arranged to arrest the shank when the hammer is moved to striking position, and a muting device secured to the shank adjacent the point of contact 15 with the abutment, substantially as described.
